DISPLAY HOLDER TAPE CARTRIDGES,
CASSETTES OR THE LIKE

Jerry G. White, 203 Melody Lane, Terrell, Tex. 75160

Filed July 1, 1971, Ser. No. 159,095

Term of patent 14 years

Int. Cl. D6—06

U.S. Cl. D6—189

FIG. 1

FIG. 3

FIG. 2

FIG. 4

FIG. 5

FIG. 1 is a front perspective view of a display holder tape cartridges, cassettes or the like, showing my new design;

FIG. 2 is a right side elevation view thereof;

FIG. 3 is a front elevation view thereof;

FIG. 4 is a rear elevation view thereof; and

FIG. 5 is a bottom plan view thereof.

I claim:

The ornamental design for a display holder tape cartridges, cassettes or the like, substantially as shown.
